ATT'YS.

UNITED STATES PATENT OFFICE.

SAMUEL B. ZIMMER, OF LOS ANGELES, CALIFORNIA.

METAL JAMB STRIP.

Application filed July 27, 1923. Serial No. 654,185.

To all whom it may concern:

Be it known that I, SAMUEL B. ZIMMER, a citizen of the United States, residing at Los Angeles, in the county of Los Angeles 5 and State of California, have invented new and useful Improvements in Metal Jamb Strips, of which the following is a specification.

This invention relates to improvements 10 in wall plastering, when the plaster adjoins a door jamb or window casing. An object of my invention is to eliminate the setting of furring strips or grounds. Another object is to eliminate the setting of casings of 15 wall openings. To accomplish this I provide a metal jamb strip such as is herein-after more fully described and claimed, reference being made to the accompanying drawing, in which:

Fig. 1 is a horizontal section of a plastered wall adjoining a door-jamb, showing the application of my metal jamb strips.

Fig. 2 is a view in perspective of the metal jamb strip of Fig. 1.

Figs. 3, 4 and 5 are horizontal sections showing modified forms of my metal jamb strips.

Referring to the drawing in which similar reference characters refer to similar 30 parts a wood block or brick 10 is set in the wall 11 to provide a fastening means for setting the door jamb 12, held in position with respect to the wall by a shim 13.

In plastering up to the door jamb, I replace the grounds by metal jamb strips 14 which are attached to the door-jamb 12. The metal jamb strip 14, shown in Figures 1 and 2, is formed of sheet metal and comprises a flat flange 14^a, a portion 1 extending outwardly at right angles from one edge of the flange 14^a, a portion 2 extending from the portion 1 at right angles in a plane parallel with the flange 14^a and in the opposite direction, a portion 3 extending from the portion 2 parallel with the portion 1, a portion 4 extending from the portion 3 in line with the flange 14^a and in the opposite direction, a corner 16 at the outer edge of the portion 4, and a flange 15 extending from the corner 16 at an angle of about 45 degrees. The jamb strip forms a metal corner for the plaster and the molding to join the plaster with the jamb 12, the face of the plaster being at right angles to 55 the jamb.

In Figs. 1 and 3, the metal jamb strip is provided with a flange 14^a, which is applied to the back of the door-jamb 12 by fasteners such as nails 14^b. The metal jamb strips may take any one of a number of moulded 60 shapes. Figs. 1, 2 and 5 show metal jamb strips having rectangular portions as at 14^c, while Fig. 3 shows the employment of a rounded portion 14^d, and Fig. 4, the use of a combination of rectangular and rounded 65 portions as at 14^e.

All strips, however, are provided with a turned over flange 15 forming the corner 16. It is readily seen that the plasterer may easily build his plaster out flush with the 70 corner and to the desired depth, some plaster squeezing around in back of the flange 15, which upon hardening serves to make the jamb strip solid with the wall. It is also seen that these strips may be applied either where the adjoining plaster 75 forms a straight wall or forms a corner, shown in Fig. 1.

As shown in Figs. 4 and 5, it may be desirable to attach the jamb strips after the 80 jamb is set. In this case a wooden filler 18 is provided as a core in the metal jamb strip, and the nails 14^b are driven through the jamb strip 14 and filler 18 into the side 85 of the door jamb.

The metal jamb strips serve as a finish moulding at the juncture of plaster and door jamb, as well as a guide for the plasterer as to the depth of his plaster. The setting of the door jamb having attached 90 thereto the metal jamb strips reduces the setting of the grounds and the setting of the door jamb to a single operation, the jamb being set to a true joining with the plaster.

Changes may be made within the spirit 95 of the invention.

What is claimed is:

1. A jamb strip formed of sheet metal and comprising a flange, a portion extending at right angles from one edge of the flange, a second portion extending at right angles from the first portion, a third portion extending at right angles from the second portion parallel with the first portion, a fourth portion extending at right 100 angles from the third portion in line with the flange, a corner at the outer edge of the fourth portion, a flange extending from the corner at an angle of about 45 degrees, said jamb strip being adapted to form a metal 110

corner for plaster, and to form a molding between the plaster and a jamb set at right angles to the plaster.

2. A jamb strip formed of sheet metal and comprising a body portion, flanges extending in opposite directions from said body portion, one of said flanges serving as a nailing strip, the other of said flanges forming a corner by having a portion bent 10 at an acute angle to the body of the last mentioned flange.

3. A jamb strip formed of sheet metal comprising a flange adapted to form a nailing strip, a body portion integral with said flange, a second flange integral with said 15

body portion and parallel with the first mentioned flange, said second flange adapted to form a corner by having a portion bent at an acute angle to the body of said second flange. 20

4. A jamb strip formed of sheet metal comprising a body portion forming a corner molding, flanges integral with said body portion and extending in parallel and opposite directions, one of said flanges serving as a nailing strip and the other serving as a ground gage for plaster. 25

In testimony whereof I have signed my name to this specification.

SAMUEL B. ZIMMER.
